US0D1091841S

(12) **United States Design Patent** (10) Patent No.: **US D1,091,841 S**
(45) Date of Patent: ** Sep. 2, 2025

(54) **FEMALE TREATMENT DEVICE**

(71) Applicant: **ZIGI CARMEL INITIATIVES & INVESTMENTS LTD.**, Tel-Aviv (IL)

(72) Inventors: **Shlomi Ben-Ner**, Modi'in (IL); **Stephanie Bekkers**, Tel Aviv (IL); **Eran Mordechay**, Rishon LeZion (IL)

(73) Assignee: **ZIGI CARMEL INITIATIVES & INVESTMENTS LTD**, Tel Aviv (IL)

(**) Term: **15 Years**

(21) Appl. No.: **35/520,188**

(22) Filed: **Feb. 11, 2024**

(80) **Hague Agreement Data**

Int. Filing Date: **Feb. 11, 2024**

Int. Reg. No.: **DM/235494**

Int. Reg. Date: **Feb. 11, 2024**

Int. Reg. Pub. Date: **Mar. 8, 2024**

(30) **Foreign Application Priority Data**

Aug. 15, 2023 (CN) 202330522131.6

(51) **LOC (15) Cl.** **24-01**

(52) **U.S. Cl.**

USPC **D24/215**
